FRANK J. DEVLIN, OF FOREST HILLS, NEW YORK

DISPLAY DEVICE

Application filed November 19, 1932. Serial No. 643,364.

This invention relates to improvements in display devices and has particular reference to a price-indicating sign, for use in dispensing various commodities in measured quantities.

An object of the invention is to provide an improved device of simple, practical, and inexpensive construction, which may be employed for indicating current prices of given quantities of a commodity, such as gasoline, or the like.

Another object is to adjustably mount a plurality of panels within the casing of the device, so that any one of said panels could be moved and secured in a position wherein indicia thereon would be visible to an observer and said indicia read in conjunction with other changeable indicia on the device to determine the price of a certain quantity of the commodity being sold.

The above and other objects will appear more clearly from the following description, when taken in connection with the accompanying drawing, which illustrates a preferred embodiment of the inventive idea.

In the drawing:

Figure 1 is a front elevation of the device, partially broken away, with one of the indicating panels in operative position.

Figure 2 is a fragmentary view similar to Fig. 1, with all the panels in inoperative position.

Figure 3 is a vertical longitudinal section through the device, and

Figure 4 is a plan view of a dial used in connection with the device.

The device is shown as comprising a rectangular frame 5 which is provided with a front wall 6 that extends from the bottom to a point short of the upper end of the frame, thus forming an opening 7 in the front of the device. A rear wall 8 projects downwardly from the top of the frame, and its lower end terminates at approximately the level of the upper end of the front wall, said ends slightly overlapping. Thus the rear of the casing formed in this manner is left open for a major portion of its height for a purpose which will presently appear.

Mounted in the front wall 6 adjacent its

bottom is a pin 9 which rotatably supports a dial 10 having a plurality of numbers 11 arranged about its periphery to designate cent denominations, said numbers being successively exposed through an opening 12 so as to be associated with a fixed dollar numeral 13 inscribed on the front wall 6. One blank space 14 on the dial 10 is provided for registration with the opening 12 when the exact cost of the commodity being sold can be designated by the single numeral 13. Adjustment of the dial 10 may be effected from the rear of the casing below said rear wall, and in order to secure said dial in adjusted positions, a wing nut 15 is threaded upon the pin 9 for engagement with the wall 6, so as to bind the dial against the washer 16 interposed between said dial and wall.

Passing through the upper end of the front wall 6 and the lower end of the rear wall 8 is a pin 17, upon which are rotatably suspended three panels 18, 19, and 20, of segmental form and each having a projecting tab 21 identified with a different numeral 22, said tabs projecting radially in different directions from the panels adjacent the pin 17, so that either one may be grasped to slightly rotate the panel carrying the same, after which said panel may be reached from the rear of the device and turned to the desired position. Normally, the panels assume a position behind the front wall 6, as shown in Fig. 2, with only the tabs 21 and the numerals thereof exposed above the upper edge of said wall, and they may be secured in such inoperative position, or either one of them in an adjusted operative position, as shown in Figs. 1 and 3, by a wing nut 23 on the pin 17, operating in a manner similar to the nut 15.

When using the device for the sale of gasoline, for instance, each panel has inscribed thereon a numeral indicating the number of gallons which may be purchased for the amount designated by the numerals 11 and 13 and, in addition, another such numeral may be placed on the front face of the rear wall 8, so as to be visible through the opening 7 when all the panels are in their normal or inoperative positions. Thus the numeral "6" (Fig. 2) is inscribed on the wall 8, while the

large numerals "7", "8", and "9" corresponding to the numerals 22 are placed upon the respective panels 18, 19, and 20, either one of which, when swung to its operative position, will cover the numeral "6" on the rear wall 8 and expose its own numeral through the opening 7.

What is claimed is:

- 10 1. A display device comprising a casing consisting of a frame, a front wall for the frame terminating short of one end thereof to provide an opening, a rear wall for said frame extending from said end thereof to a point approximately in alignment with the end of said front wall forming an edge of said opening, indicia on said rear wall visible through said opening, a pivot rod connecting said walls adjacent said openings, a plurality of panels each mounted for rotary movement 20 on said rod and having indicia thereon, said panels being normally positioned behind said front wall and each being adjustable to a position in alignment with said opening and

in front of the indicia on said rear wall, and means on said rod for securing said panels in normal and adjusted positions.

2. A display device comprising a casing consisting of a frame, a front wall having an opening at its upper end, and another opening below the first named opening, a rear wall extending downwardly from the top of said frame and terminating at a point short of the bottom of said frame, whereby access may be had to the interior of said casing from the rear thereof, a dial rotatably mounted in back of said front wall, so as to expose indicia thereon through the second named opening in said wall, and a plurality of panels also rotatably mounted within said casing, and each movable from a position behind said front wall to an exposed position in alignment with said first named opening, said dial and panels being accessible for rotative adjustment through the open portion of the rear wall of said casing.
